UNITED STATES PATENT OFFICE.

JOHN J. A. MILLEE, OF DENVER, COLORADO, ASSIGNOR TO THE AUTOMATIC FURNACE OXIDATOR AND MANUFACTURING COMPANY, OF DENVER, COLORADO, A CORPORATION OF COLORADO.

AUTOMATICALLY-OPERATING SHUTTER OPENING AND CLOSING MECHANISM FOR FURNACE OXIDATORS.

Application filed October 9, 1922, Serial No. 593,474. Renewed March 31, 1926.

My invention relates to improvements in automatically operating shutter opening and closing mechanism for furnace oxidators.

5 The object of the invention is to provide a shutter-controlled air heating device for furnace doors, and mechanism for operating said shutters, whereby, when the door is closed after coaling, the shutters are 10 automatically opened to permit the passage of air through said heater and into the furnace, means being cooperatively connected with the shutter operating mechanism for gradually closing said shutters within 15 a predetermined period.

Further, to provide a pre-heater for furnace doors, shutters for controlling the entrance to said pre-heater, and mechanism for automatically opening said shutters 20 simultaneously with the closing of the furnace door, whereby air is permitted to pass through said pre-heater and into the furnace above the coal bed, the closing of said shutters within a predetermined period being 25 determined by a combined gravity and spring-operated oil valve which is also lifted by said shutter opening mechanism simultaneously with the opening of said shutters.

30 Further, to provide in connection with the shutter opening mechanism of oxidators or smoke abating attachments of this character, a combined gravity and spring operated oil valve comprising a valved piston 35 which is raised in an oil cylinder by said shutter opening mechanism simultaneously with the opening of the shutters, the length of time required for the descent of said piston, and consequently for the closing of 40 said shutters, being determined by the adjustment of the valve in said piston whereby a regulated supply of heated air is admitted to the combustion chamber of the furnace for a predetermined period after the coaling 45 operation, the said air being discharged over the coal bed by which it is mixed with the combustible gases and floating particles of carbon and tar, thus causing complete combustion of these particles and the consequent 50 elimination of the unconsumed product, or smoke.

These objects are accomplished by the

mechanism illustrated in the accompanying drawings in which:

Fig. 1 is a front view of a furnace door 55 equipped with the improved oxidator or smoke abating device.

Fig. 2 is a top view of Fig. 1.

Fig. 3 is an enlarged sectional view on the line 3—3 of Fig. 1, showing the parts 60 of the operating mechanism in the positions they assume immediately upon closing the furnace door, the oil valve being on the point of descending.

Fig. 4 is a sectional view through the 65 mechanism housing on the line 4—4 of Fig. 1 showing the oil valve at the limit of its descent.

Fig. 5 is a horizontal sectional view of the mechanism housing on the line 5—5 of 70 Fig. 1 showing the position of the parts when the furnace door is open, the oil valve being down.

Fig. 6 is a plan view of the mechanism housing, the cover thereof being removed, 75 and the parts being in the same position indicated in Fig. 5.

Fig. 7 is a front view of the air heating device or pre-heater which is bolted to the inside of the furnace door.

Fig. 8 is a sectional view on the line 8—8 of Fig. 1, the shutters being closed, and a portion only of the pre-heater being shown. And

Fig. 9 is a front view—full size—of a 85 portion of one of the shutters, showing the manner of pivoting the same to a supporting strip.

The abatement of furnace smoke can be 90 accomplished only by the complete combustion in the furnace of the floating particles of tar and carbon. To bring about this result, air in quantities sufficient for the complete oxidation of all combustible matter, should be admitted to the furnace, over 95 the fire, immediately after coaling, and thoroughly mixed with the combustible gases and floating particles of carbon and tar, and this quantity of air should be gradually reduced as the distillation of the volatile combustibles nears completion. The 100 improved device, which is adapted to be attached to a furnace door, meets these requirements by means of a combination of

elements which are arranged and constructed as will hereinafter appear.

Referring to the accompanying drawings:

The numeral 1, indicates the front wall of a furnace, and 2, the fire door which is hinged to the front wall in the usual manner. The door is provided with a circular opening 3, which is about ten inches in diameter, and an improved air pre-heater is bolted to the back of the door to register with the opening 3. The pre-heater comprises a flared band 4, which at its smallest end is slightly greater in diameter than the hole 3, in the door, and this smaller end is provided with integral feet 5, which are bolted to the door by bolts 6.

A series of thin radial plates 7, connect the band 4, with a central tubular member or hub 8, the band, the plates and the hub forming an integral structure. The hub 8, is somewhat longer than the width of the band, and the outer edges of the plates 7, are outwardly curved from the edge of the band 4, to the outer end of the hub 8, as clearly shown in Fig. 2.

Radial plates 9, also extend inwardly from the band 4, and alternate with the plates 7, but the plates 9, terminate before reaching the hub 8, as shown in Fig. 7.

When the furnace door is closed, the pre-heater extends into the combustion chamber of the furnace, and therefore becomes heated to a high degree of temperature, so that atmospheric air passing through it, between the plates 7, and 9, becomes highly heated before passing over the coal bed in the furnace, for a purpose which will hereinafter appear.

40 A square frame 10, of the same diameter as the hole 3, in the door is bolted to the door by the bolts 6, which secure the pre-heater, the frame having apertured lugs 11, on three of its sides through which the said bolts pass.

45 The frame is provided with a series of overlapping shutters 12, in the form of thin metal blades having apertured lugs 13, on their opposite ends to receive pivot pins 14, which may be mounted either in opposite 50 sides of the frame 10, or in metal strips 15, which are screwed to the sides of the frame, as shown in Figs. 1 and 8. The central shutter 12, has a lug 13, on one end only, and upon the opposite end of this shutter is riveted the forked end of a shaft 16, which extends through the adjacent side of the frame 10, and through the side of a housing 17, which is secured to the furnace door by bolts 18, which extend through the rear side of 55 the housing, and by a bolt 19, which passes through a lug 20, on the bottom of the housing, the function of the shaft 16, being to operate the shutters through the medium of mechanism to be hereinafter described.

60 Each shutter 12, is provided with a pair

of apertured ears 21, all of which pairs are in the same vertical line, and a flat bar 22, is passed between the ears of all of the shutters and is pivotally connected to each pair of ears by a pin 23. Thus, when the central 70 shutter is turned by the shaft 16, as will presently be described, the other shutters are also turned, through their connection with the bar 21.

The housing 17, is separated into two 75 chambers 24 and 25, by a vertical partition 26. The chamber 24, incloses the mechanism which operates the shaft 16, but the bottom of the chamber 25, is formed with a depending smooth bore cylinder 27, which 80 opens into the said chamber 25, at its upper end. A hollow piston 28, is mounted in this cylinder and this piston is wide open at the bottom and its upper end is formed with four radial arms or spokes 28^A, to which are 85 integrally connected an axial hub 29, in which is inserted the reduced portion of a circular rack bar 30, which is held in the said hub by a pin 31, which passes through the hub and through a groove in the said 90 reduced portion of the rack bar. The rack bar has an axial hole 32, extending through the same, the lower portion of which is threaded, and a stem 33, is screwed into this threaded portion of the hole, and extends 95 down through an opening 34, in a partition 35, located about midway of the length of the piston.

The lower portion of the stem 33, is reduced in diameter, as shown at 36, forming a shoulder 37, at the junction of the two diameters, and a disk valve 38, having an axial hole, is slipped on the reduced portion 36, and is normally held against the shoulder 37, by a spiral coil spring 39, which surrounds the portion 36, of the stem and is held in place by a pin 40, which passes through the portion 36, and engages the bottom coil of the spring 39. The housing 17, is closed by a cap 41, having a threaded hole 42, which is in line with the hole 32, in the rack bar 30.

The upper end of the stem 33, is formed with a screw driver slot, and by passing a screw driver down through the hole 42, in the cap and into the hole 32, in the rack bar 30, the valve stem 33, may be adjusted to vary the distance between the disk valve 38, and the bottom face of the partition 35, for a purpose to be hereinafter set forth.

The hole 42, in the cap is normally closed by a screw 43.

The shaft 16, which is secured at one end to the central shutter 12, and which passes through the adjacent side of the housing 17, 12. also passes through the chamber 25, and through a bearing hole in the partition 26, of the said housing, and into the chamber 24, and its free end has rigidly secured thereon a small segment gear 44, while the portion 13.

of the shaft which lies within the chamber 25, carries a larger segment gear 45, which meshes with the rack bar 30, thereby to raise the piston 28, as will be fully set forth hereinafter. The circular rack bar will always remain in mesh with the segment gear 45, irrespective of the axial turning movements of the piston 28, in its cylinder 27. The small segment 44, is operated to turn 10 the shaft 16, in the following manner:

A knob 46, has a reduced threaded portion 47, which is screwed into an aperture in the front wall of the housing 17, centrally of the lower portion of the chamber 24, and 15 the threaded portion 47, has a short axial reduced portion 48, which projects into the chamber 24. An axial threaded hub or boss 49, is formed on the front of the knob and an axial hole 50, extends through the knob and 20 from end to end, the inner end of the hole terminating in a flared enlargement 51, in the end of the reduced portion 48, of the knob. The boss 49, is provided with a threaded cap 52.

25 A piece of tubing 53, is slidably mounted in the hole 50, of the knob, and a coil spring 54, is interposed between the outer end of this tube and the cap 52. The inner end of the tube projects through a hole in the back of the housing 17, and through a hole or recess 55, in the adjacent edge of the door 2, and when the door is opened, the tube is projected about an inch beyond the inner face of the door by the spring 54, and when 30 the door is closed, the inner end of the tube engages the front wall of the furnace, and slides the tube back against the action of the spring 54, for a purpose to be later explained.

35 A slide 56, in the form of a cylindrical block having an axial hole 57, and a series of annular teeth 58, which mesh with the segment gear 44, is mounted on the tube 53, between the back wall of the housing and the projecting portion 48, of the knob, and 40 an internal annular groove 59, is formed in the wall of the axial hole in the slide, the front shoulder of said groove being slightly beveled or undercut as shown. A coil spring 50 surrounds the forward end of the slide and also the projecting portion 48, of the knob and is held under compression between the front tooth of the slide and the end of the threaded portion 47, of the knob. The 45 function of this spring is to assist in moving the slide rearward on the tube, until it engages the rear wall of the housing 17, after the said slide has been moved forward on the tube in a manner, and for a purpose to be hereinafter set forth. A slot 60, is cut through the wall of the tube, and extends the greater part of the length of the tube, and a latch 61, of slightly less length than

50 the length of the slot 60, is inserted through 55 the slot and into the tube and the outer end

of this latch is pivoted to the tube by a pin 62.

Intermediate of its length the latch is widened and its upper edge is formed with a short incline 63, where the wide portion of the latch merges into the narrow forward portion thereof. Rear of the incline 63, the upper edge of the latch is formed with a recess 64, of suitable length, and the rear shoulder 65, of this recess forms a catch 75 which is adapted to engage the undercut shoulder of the annular groove 59, in the slide 56, when the furnace door is opened, as will later appear. An expansion coil spring 66, is interposed between the under edge of the rear end of the latch, and the wall of the tube, for the purpose of forcing the free end of the latch outward.

A bolt 67, is screwed into the rear end of the tube 53, and one or more washers 68, 85 may be interposed between the head of the bolt and the end of the tube, thus providing for slight variations in the inward sliding movement of the tube when the furnace door is closed.

In operation, the cylinder 27, is filled with a suitable oil which may also extend to within a slight distance of the top of the partition 26, and assuming that the piston is at the limit of its downward stroke, the 95 segment gear 45, will be in the position shown in Figs. 4 and 6, while the segment gear 44, will be in the position shown in dotted lines in Fig. 4, and in full lines in Fig. 6, and the slide block 56, will be at the 100 limit of its rearward position, or in contact with the rear wall of the housing as shown in Fig. 5. The tube 53, is in the position shown in Fig. 3, and the latch 61, has been forced back to lie entirely within the tube 105 by the engagement of its incline 63, first with the flared end 51, of the hole 50, in the knob, and then by the engagement of the upper edge of the wide part of the latch with the wall of the said hole 50, as clearly shown in Fig. 3, which shows the position of the parts at the instant the door is closed, and just as the valve begins to descend.

When the furnace door is opened for coaling, the spring 54, in the knob throws the tube out to the position shown in Figs. 5 and 6, and the wide point of the latch passes out of the hole in the knob by which it was held inoperative within the tube, but the rear end of the latch lies within the front end of the 115 slide, which holds it against outward movement until the end portion of the latch is opposite the annular groove 59, when the spring 66, throws the latch out so that its rear end portion enters the groove 59, and 125 the catch 65, of the said latch engages the under cut shoulder of the said groove as clearly shown in Fig. 5.

When the door is closed, the head of the bolt 67, in the end of the tube 53, engages 130

the face of the front wall of the furnace, and the tube is thereby moved to the position shown in Fig. 3, carrying the slide with it until the incline 63, on the latch engages the flared end of opening in the knob, and then passes into the opening, when the latch is thrown inward and out of engagement with the said under cut shoulder of the slide. As the slide is moved inward by the latch, the segment gear 44, is thereby turned to the position shown in Fig. 3, and, simultaneously, the segment 45, is also turned to the position shown in Fig. 3, thereby lifting the piston through its connection with the circular rack bar 30, with which the said gear 45, meshes.

As the piston is lifted through the body of oil in the cylinder, the oil passes down through the top of the piston and through the opening 34, in the partition 35, of the piston, moving the disk valve 38, down against the action of the spring 39; but when the piston reaches the limit of its upward movement, the disk valve is thrown against the shoulder 37, of the stem 33, by the spring 39, and the valve begins its descent through the oil in the cylinder, under the combined action of gravity, and the expansive force of the spring X, which pushes the slide 56, rearward until it engages the rear wall of the housing, as shown in Figs. 5 and 6.

As the piston rises, the shutters 12, are swung open, and atmospheric air is drawn into the furnace through the preheater, by which the said air is heated to a high degree of temperature and passes over the coal bed, thoroughly mixing with the combustible gases and floating particles of tar and carbon, thereby causing complete combustion in the furnace with the consequent elimination of smoke. The length of time required for the piston to descend, and the consequent gradual closing of the shutters, is determined by the adjustment of the valve stem, by which the space between the disk valve 38, and the partition 35, is either increased or diminished, thus regulating the flow of oil through the piston.

Having described my invention, what I claim as new and desire to secure by Letters Patent is:

1. In a device of the character described, the combination with a furnace door, having an air heating device on the inner side of the door, and shutters for admitting air to the furnace through said heating device, of slidable means operated by the closing of the door, a member slidably mounted on said slidable means, and gearing operated by said slidable member for automatically opening said shutters, and a oil-controlled gravity actuated mechanism for closing said shutters.

2. In a device of the character described,

the combination with a furnace door, of an air heating device on the inner face of said door, shutters for admitting air to the furnace through said heating device, a spring controlled slide member which is projected when the door is opened and retracted by the closing of the door, a toothed member slidable on the spring controlled slide member, gearing operated by the toothed member for opening said shutters simultaneously with the closing of the door, and an oil controlled gravity actuated mechanism for closing said shutters.

3. In a device of the character described, the combination with a furnace door, of an air heating device on the inner face of the door, shutters for admitting air to the furnace through said air heating device, a spring-projected slide member which is released by the opening of the door, and retracted by the closing of the door, a toothed member movable with the slide member when the same is retracted, gearing operated by the toothed member for opening the shutters simultaneously with the closing of the door, means to disconnect the toothed member from the spring projected member, when the latter is at the limit of its retracted movement, and an oil controlled gravity actuated mechanism for closing said shutters.

4. In a device of the character described, the combination with a furnace, of an air heating device on the inner face of said door, shutters for admitting air to the furnace through said air heating device, a spring-projected slide which is released by the opening of the door and retracted by the closing of the door, a toothed block mounted on and movable with said slide when the same is retracted, gearing operated by the toothed block for opening said shutters simultaneously with the closing of the door, a latch for connecting the toothed block to the slide when the latter is retracted, means for disconnecting the latch from the toothed block when the slide reaches the limit of its retracted movement, and means movable with the gearing for gradually closing said shutters within a predetermined period.

5. In a device of the character described, the combination with a furnace door, of an air heating device on the inner face of the door, shutters for admitting air to the furnace through said air heating device, a spring-projected bar which is released by the opening of the door and retracted by the closing of the door, a circular toothed block slidably mounted on said bar, and means for locking the block to the bar when the bar is retracted, a shaft connected with the shutters, and a gear on said shaft operated by the toothed block to open the shutters as the door is closed, means for releasing the toothed block when the bar is retracted.

to the limit of its movement, and means movable with the gearing for reversing the toothed block and for gradually closing the shutters within a predetermined period.

5 6. In a device of the character described, the combination with a furnace door, of an air heating device on the inner face of said door, shutters for admitting air to the furnace through said heating device, a spring-projected bar which is released by the opening of the door and retracted by the closing of the door, a circular toothed block which is slidably mounted on said bar, a latch carried by the bar for engaging and moving the block with the bar, when the same is retracted, a shaft connected with said shutters, and a gear on the shaft operated by the block to open said shutters as the door is closed, means for throwing the latch to release the block when the bar is retracted to the limit of its movement, and gravity means for reversing the shaft whereby the toothed block is reversed and the shutters are closed within a predetermined period.

20 7. In a device of the character described, the combination with a furnace door, of an air heater on the inner face of the door, shutters connected to swing in unison for admitting air to the furnace through said heater, a bar mounted on the door, a spring for projecting said bar when the door is opened, said bar being retracted by engagement with the furnace wall when the door is closed, a circular toothed block slidably mounted on the bar, a latch pivotally mounted in the bar for engaging and moving the toothed block with the bar when the same is retracted, a shaft connected to one of said shutters and a gear 25 on said shaft in mesh with the toothed block whereby the shaft is turned to open the shutters when the door is closed, means for tripping the latch to release the block when the bar is retracted to the limit of its movement, an oil controlled gravity actuated valved piston, having a toothed rod and a gear on said shaft in mesh with said rod, whereby the piston is raised simultaneously with the opening of the shutters while its descent effects the closing of the shutters and a reverse movement of the toothed block.

30 8. In a device of the character described, the combination with a furnace door, of an air heater on the inner face of the door, shutters mounted on the door and connected to swing in unison, for admitting air into the furnace through said heater, a housing on the door having a depending oil holding cylinder, a shaft mounted in the housing and connected to the axis of one of said shutters, a bar slidably mounted in said housing, one end of which bears against the front wall of the furnace when the door is closed, and 35 a spring for projecting said bar when the

door is opened, a slide on said bar having annular teeth, a gear on said shaft in mesh with said teeth, a valved piston in said cylinder having a toothed rod, a gear on the shaft in mesh with the toothed rod, and a spring-actuated latch in said bar for engaging said toothed slide when the door is opened and the bar is projected, whereby when the door is closed the bar with the latch is moved inward thereby turning the shaft to open the shutters and raise the piston; an abutment for tripping the latch when the door is fully closed to release the slides, the descent of the piston causing a reverse rotation of the shaft whereby the shutters are gradually closed and the slide restored to its normal position.

40 9. In a device of the character described, the combination with a furnace door, of a housing thereon having a depending oil holding cylinder, and a knob having an axial bore which is closed at its outer end, a tubular bar slidably mounted in said bore and extending through the housing and door, its front end normally bearing against the furnace wall, a spring interposed between the rear end of said bar and the closed end of said bore to project said bar when the door is opened, a slide mounted on said bar having annular teeth and in normal engagement with the back wall of the housing, said slide having an internal annular recess, a shaft mounted in the housing and extending beyond one side of the same, a gear on said shaft in mesh with said toothed slide, a piston in said cylinder having an adjustable valve and a toothed rod, a gear on the shaft in mesh with the toothed rod, an air heater on the inner side of the door, shutters on the door connected to swing in unison and adapted to admit air to the furnace through said heater, the extended end of said shaft being connected to the axial portion of one of said shutters, a spring actuated latch in said tubular bar which is adapted to engage one end of the annular recess in the said slide when the tubular bar is projected, whereby when the door is closed the bar with the latch is moved inward thereby turning the shaft to open the shutters and raise the piston, said latch having a portion which is engaged by the wall of the bore of the knob as the bar slides into the knob, whereby the latch is tripped to release the slide, permitting the valve to descend by gravity to close the shutters and restore the slide to its normal position.

45 10. In a device of the character described, the combination with a furnace door, an air heater thereon and shutters for admitting air to said furnace through said heater, of a slide bar moved in one direction by the closing of the door, a slide thereon, means for locking the slide to the bar and means operated by the slide for opening the shutters.

ters simultaneously with the closing of the door, means for releasing the slide when the door is fully closed, gravity means for reversing the movement of the slide and at the same time gradually closing the shutters, and a spring for projecting the slide bar beyond the inner face of the door when the door is opened.

11. In a device of the character described, the combination with a furnace door, an air heater thereon and shutters for admitting air into the furnace through said heater, of a slide bar moved in one direction by the closing of the door, a slide thereon, a latch for locking the slide to the bar, and means operated by the slide for opening the shutters simultaneously with the closing of the door, means for releasing the latch when the door is fully closed, gravity means and a spring for reversing the movement of the slide and at the same time gradually closing the shutters, and a spring for projecting the bolt when the door is opened.

12. The combination with a furnace door, shutters thereon adapted to turn in unison, a housing on the door, a shaft mounted in said housing and secured at one end to the axial portion of one of the shutters, of a knob threaded into said housing having an axial bore, a threaded boss surrounding the

outer end of the bore and a cap on said boss, the inner end of the bore being flared, a tubular bar mounted in the bore and extending through the rear housing wall and door and adapted to bear against the front wall of the furnace when the door is closed, a coal spring under tension between the opposite end of the bar and the said cap to project the bar beyond the face of the door when the door is opened, a slide mounted on the bar having annular teeth, and an internal annular groove, a spring actuated latch in said bar having a catch to engage a shoulder of the annular groove when the bar is projected, and an inclined portion for engaging the flared end of the bore and then the bore, to trip the latch and release the slide when the bar is slid inward by the closing of the door, a gear on the shaft in mesh with the toothed slide, an oil controlled valved piston having a toothed rod, a gear on the shaft in mesh with the toothed rod, a spring interposed between the end of the slide and the knob, said shaft being turned to open the shutters and raise the piston when the door is closed and said shutters being closed by combined spring action and the descending piston.

In testimony whereof I affix my signature.
JOHN J. A. MILLER.
